FLAME CONTROL FOR FLUID FUEL BURNERS

Filed March 4, 1936

UNITED STATES PATENT OFFICE

2,105,626

FLAME CONTROL FOR FLUID FUEL
BURNERS

Walter W. Williams, Bloomington, Ill.

Application March 4, 1936, Serial No. 67,020

4 Claims. (Cl. 158—28)

This invention relates to improvements in fluid fuel burners, and more particularly to an improved means for controlling the flame at initial ignition in the forced draft type of burner.

5 In the forced draft type of fluid fuel burner mechanism for domestic heating purposes, the full forces of the air and fuel under normal operating pressures are simultaneously delivered, upon initiating operation, and roaring combustion noise occurs upon initiating ignition of the combustible mixture much greater than the noise of combustion during the operation thereafter.

10 It is an object of this invention to control the initial delivery of fuel and air in such a manner that the noise of initial combustion is no greater than during normal operation.

15 With these and other objects in view, reference is made to the accompanying sheet of drawing which illustrates a preferred embodiment of this invention, with the understanding that detail changes may be made without departing from the scope thereof.

In the drawing:

20 Figure 1 is a view in side elevation of an electrically operated and controlled fluid fuel burner mechanism to which this invention has been applied, with parts broken away, and parts shown in section.

Figure 2 is an enlarged detail view in central 25 vertical section of the improved control device, with parts shown in elevation.

Figure 3 is a view partly in elevation and partly in section of a modification of Figure 2. Figure 30 4 is a schematic wiring diagram of the ignition circuit.

I developed a particular type of fluid fuel-burning mechanism wherein the fuel is delivered in a constant flow by a metering pump to a pressure pump which receives the fluid fuel 40 and atmospheric air and then delivers the fuel and air under pressure to a chamber wherein the pressure created therein delivers the fuel through a float-controlled valve to a fuel pipe and the air through an air pipe surrounding said fuel pipe to a nozzle where the fuel and air are delivered in the form of a spray surrounded by air under pressure from a fan blower to be ignited by an electrical ignition device. This construction is fully disclosed in my prior Patent 45 No. 1,831,277, dated November 10, 1931, and as this invention relates to a particular control to be added to such structure, it is thought that the above description is sufficient to the understanding of this invention.

50 Figure 1 illustrates an embodiment of this in-

vention as applied to a burner mechanism of the type above described. The burner mechanism illustrated includes a casing 1 supported upon legs 2 which in turn support a fan blower housing 3 mounting a blower for delivering air under 5 pressure through a draft pipe 4. The blower driving shaft is driven by an electric motor, not shown, and said shaft is extended to operate the rotor 5 of a pressure pump within a housing 6 extending from the blower housing 3 and a fluid 10 fuel metering pump 7 adapted to deliver fluid fuel to the interior of said pressure pump. The pressure pump is provided with an air intake 8 and delivers the air received therefrom and the fuel from the metering pump under pressure 15 through pipe 9 to the interior of the closed chamber 10 formed by the casing 11 supported upon the casing 1.

The burner nozzle 12 is mounted concentrically within the draft pipe 4 adjacent its open 20 end and adjacent the electric ignition device 13. The nozzle 12 is connected to the chamber 10 by an air pipe 14 axially mounted within the draft pipe 4 which enters said chamber adjacent its top. The nozzle 12 is also connected to the 25 chamber 10 by fluid fuel pipe 15 extending concentrically within said air pipe 14 which is extended within the chamber 10 to adjacent the bottom thereof, and the entrance of fuel therein is controlled by a float-operated valve 16 actuated by the level of the fuel within the chamber 10 received from the said pressure pump. The pressure created within the chamber 10 delivers both fuel through the fuel pipe 15 and air 30 through the air pipe 14 to the nozzle 12 where 35 the fuel is delivered in a spray into the surrounding stream of air from the blower passing through the draft pipe 4 and the combustion mixture is initially ignited by the ignition device 13. This particular construction above described 40 is fully disclosed in my prior Patent No. 1,831,277, dated November 10, 1931.

The subject matter of this invention relates to the particular construction of an air muffler attached to the air intake 8 in the casing 6 of the 45 pressure pump and the results accomplished by such construction.

It is customary in the electrically operated and controlled fluid fuel burner mechanism above described, when the space to be heated has 50 reached the predetermined degree of temperature for the room thermostat to open the circuit to the burner and the mechanism ceases to operate. The motor, fan blower, fuel metering pump, and air and fuel pressure pump remain idle until a 55

call for heat initiates operation. In accordance with this invention, when operation is initiated, the air intake to the air and fuel pressure pump is throttled, so that when the said pump first starts to operate, no air is drawn in through the air intake and the suction resulting from continued operation gradually opens the air intake until the normal amount of air passes therethrough. The result is that at the start of operation the pressure within the chamber 10 is built up gradually until normal operating pressure is reached and the amount of air and fuel delivered from the chamber 10 to the nozzle enters the nozzle 12 at a lesser rate and gradually increases to normal as the pressure within the chamber becomes normal. The result is that the combustible mixture formed at the nozzle ignites with smaller flame increasing to normal and the ignition occurs without the initial roar.

20 The improved air muffler for producing the above result includes a cylindrical casing 17, preferably formed with a closed lower end 18 and a removable cover 19 for the upper open end. An aperture 20 corresponding in size to the air intake 8 of the pump casing 6 is provided in the casing 17 adjacent its upper end which is held in alignment with the air intake 8, in any desired manner, such as by screws 21 passed through ears 22 provided upon the casing 17 to hold said casing securely upon the pump casing 6.

A dash-pot controlled piston 23 is mounted to reciprocate within the casing 17, which, in its lowermost position, will snugly fit therein. A plurality of air intake apertures 24 are arranged about the casing 17 below the under side of the piston 23 when in its lowermost position, as shown in Figure 2. The inner diameter of the casing 17 is gradually increased toward the top from the upper side of the piston 23 when in its lowermost position, and a bleeder passage 25 is provided in the piston 23 in communication with the interior of the casing 17 on each side of the piston.

When the fuel and air pressure pump starts to operate, a suction is created through the ports 8 and 20 within the casing 17 upon the upper side of the piston 23, and the piston, from its lowermost position where it obstructs the entry of air through the ports 24, will gradually be drawn upward and in so moving will gradually allow the incoming air to pass about its periphery as the diameter of the casing increases, until the normal amount of air passes through the pump intake 8. If desired, the inner walls of the casing 17 may be provided with other means for allowing the incoming air to flow in increased volume about the piston as it ascends, such as by providing a plurality of gradually deepening grooves in the walls of the casing.

60 In order to give the piston 23 sufficient weight to normally return to its lowermost position, upon cessation of operation of the fuel and air pressure pump, and to adjustably regulate the rate of upward travel thereof, it is preferable to mount the piston 23 upon a depending concentric tube 26 adapted to engage the bottom 18 to properly locate the piston at the ends of its downward travel, which tube mounts adjacent its lower end a dash-pot plunger 27 provided with one or more ball checks 28. Sufficient fluid, such as oil, is introduced into the casing 17 to co-act with the plunger 27 for the purpose desired.

Upon the upward movement of the piston 23 and plunger 27, the fluid above the plunger passes 75 through ports 29 in the tube 26 adjacent the top

of said plunger into an axial passage 30 therein, communicating with the interior of the casing 17 below said plunger. It is preferable to provide the said passage 30 with a needle valve 31 adjustably mounted within the tube 26, as shown in Figure 2. When the pressure pump ceases to operate, the weight of the piston and dash-pot mechanism attached upon the under side thereof will allow the fluid to lift the ball check 28 to accelerate the travel of the plunger.

10 It is preferable to provide the exterior of the casing 17 with a spaced-apart air strainer 32 in the form of a wire mesh cylinder to prevent foreign matter from entering the air inlet ports 24, and also provide the under side of the piston 23 with a similar cylindrical wire mesh strainer 33 to prevent the bleeder passage 25 from becoming stopped.

It is desirable to open the circuit to the ignition device after combustion has been completed 20 and this may be accomplished by the movement of the piston 23, if so desired. When the piston 23 is to be employed for this purpose, a housing 34 is substituted for the removable cover 19. The housing mounts a tiltable mercury tube switch 35 connected by wires 35^a and 35^b in the ignition circuit, shown in Figure 4, mounted upon a pivoted support 36 normally passing over the center of the casing 17 and engaged with a stop 37 within the housing 34 to support the switch in the closed position. The piston 23 is provided upon its upper side with a concentric switch operator 37^a adapted, as the piston approaches the upper end of its travel, to engage the support 36 and tilt it about its pivot to open the switch 35. To allow of this operation and still maintain the suction within the casing 17, it is preferable to employ a flexible metallic bellows 38 having a closed end normally in engagement with the under side of the support 36 when the switch is closed and its open end having an annular flange adapted to be secured between the contacting portions of the top of the casing 17 and housing 34. It is also preferable to cause the free end of the support 36 to travel over an adjustable post 39 mounted upon the stop 37 and provide a spring 40 coiled about the post 39 with its ends engaging the head of said post and upper side of said support to normally insure the returning of the switch 35 to the closed position when the piston 23 has returned to its lowermost end of travel when the mechanism ceases operation.

50 As the casing 17 with its air inlet 20 communicating with the air intake of the air and fuel pressure pump also acts as a muffler and is provided with the screens 32 and 33 to prevent foreign matter from entering the casing and pump, the interior of the cylindrical air strainer 32 may be provided with a lining of porous felt 60 41, as shown in Figure 2, if desired, to deaden the sound of the air sucked through the screen mesh of the strainer 32.

What I claim is:

1. In an electrically operated and controlled 65 fluid fuel burning mechanism having an electrical ignition circuit and including a fuel and air pump having an air intake, a cylindrical casing closed at the lower end secured over said intake air inlets provided in the wall of said casing, a piston 70 mounted to reciprocate between said air inlets and said pump air intake, means in the casing increasing the rate of air flow to said pump air intake as the piston moves in the direction of the said pump air intake, a housing secured over 75

the open end of the casing, a switch in the ignition circuit mounted within said housing, and means upon the adjacent side of said piston adapted to enter said housing as the piston approaches that end of its travel to de-energize said ignition circuit.

5. The structure of claim 1, wherein said switch is a mercury tube switch, a tilttable support for said switch pivotally mounted within said housing 10 to extend over the axis of said housing, and said operating means includes an axial projection mounted upon said piston adapted to tilt said support about its pivot.

6. The structure of claim 1, wherein said switch 15 is a mercury tube switch, a tilttable support for said switch pivotally mounted within said housing to extend over the axis of said housing, and said operating means includes an axial projection mounted upon said piston adapted to tilt

said support about its pivot, and wherein a flexible metallic bellows having a closed end and an annular flanged end is secured by its flange between the housing and casing with its closed end engaging the under side of said switch support, 5 whereby the suction is maintained within the casing during operation of the pump.

7. The structure of claim 1, wherein said switch is a mercury tube switch, a tilttable support for 10 said switch pivotally mounted within said housing to extend over the axis of said housing, and said operating means includes an axial projection mounted upon said piston adapted to tilt said support about its pivot, and means within the housing co-acting with the pivoted switch support to contract the said bellows upon the movement of the piston away therefrom.

WALTER W. WILLIAMS.
